OBTAINING NEUTRAL DISTILLATES FROM PETROLEUM

James P. Hoffman, Wilmington, Del., assignor to Sun Oil Company, Philadelphia, Pa., a corporation of New Jersey

Filed Dec. 10, 1956, Ser. No. 627,229

5 Claims. (Cl. 208—263)

This invention relates to the refining of petroleum, and more particularly to a novel manner of recovering naphthenic acids and obtaining high boiling neutral lubricating oil distillates.

It is known in the art to refine petroleum containing lubricating oil constituents by vaporizing a portion of the petroleum charge and contacting the vapors with a liquid alkaline material, containing free alkali such as caustic soda. A typical manner of operation involves the use of a vacuum distillation tower containing a flash zone in a lower portion thereof, an alkali treating zone in an intermediate portion thereof, and a rectification zone in an upper portion thereof. The petroleum charge, e.g. reduced naphthenic crude, is introduced at an elevated temperature into the flash zone, which is maintained under high vacuum, e.g. about 25 to 100 mm. of Hg absolute. The evolved vapors are passed upwardly through the trays constituting the treating section and are countercurrently contacted with a liquid alkaline material which passes downwardly from tray to tray in the treating section, being withdrawn from the lowest tray in the treating section, and a portion thereof returned to the top tray of the treating section.

Naphthenic acid vapors contained in the vaporized oil react with alkali metal hydroxide to produce alkali metal naphthenates which become incorporated in the liquid alkaline material. These naphthenates are recoverable from the alkaline material by known means and constitute a valuable product of the process. Higher boiling hydrocarbon constituents of the vapors passing through the treating zone become condensed therein and are incorporated also in the liquid alkaline treating agent. The treated vapors pass from the treating section to the rectification section, and are rectified in conventional manner to obtain a plurality of lubricating oil distillates of varying boiling point and viscosity.

In such operation, it is extremely difficult to produce, in addition to naphthenates, good yields of lubricating oil distillates having high boiling range and high viscosity, e.g. Saybolt Universal viscosity at 210° F. of 100 seconds to 200 seconds or more. In order to produce good yields of such distillates as condensates in the lower part of the rectification zone, it is necessary to maintain relatively high temperatures in the alkali treating zone. The use of such high temperatures frequently results in excessive decomposition of organic materials in the treating zone, such decomposition resulting in carbonaceous deposits which tend to plug up the apparatus and otherwise interfere with the operation.

For these reasons, it has been difficult or impossible heretofore to produce, in a process involving vapor phase alkali treatment, as heavy lubricating oil distillates as are desired in many instances. The present invention provides a novel manner of obtaining, in such processes, heavy lubricating oil distillates having satisfactory properties for many desirable uses, such distillates being ob-

2

tained without adverse effect on the operation in the alkali treating section.

According to the present invention, petroleum containing lubricating oil constituents is distilled to obtain a first vaporized portion containing naphthenic acids, which is contacted with liquid alkaline material, as in the alkali treating section of a vacuum tower as described previously. The treated vapors are then passed into the rectification section, wherein various lubricating oil condensates are produced. The extent of the distillation is controlled in such a manner that excessive temperatures are avoided in the alkali treating section, the liquid temperature on the lowest tray thereof being within the approximate range from 575° F. to 725° F., and preferably not higher than 675° F. Consequently the heaviest lubricating oil condensates obtained in the rectification section are relatively low boiling, and are lower boiling than lubricating oil distillates obtained in further operations as subsequently described.

20 The heaviest lubricating oil constituents of the petroleum charge are contained in the residue from the distillation in the vacuum alkali tower, and in one embodiment of the invention, these constituents are obtained as distillate in a subsequent distillation of the residue. This 25 distillate is then contacted with hydrogen under conditions subsequently more fully described, to obtain selective hydrogenation of constituents of the distillates which would otherwise cause undesirable properties. The distillates thus obtained have satisfactory properties for various 30 applications, and are in general superior to distillates of corresponding boiling range and viscosity which can be obtained in similar yield in a conventional process involving alkali treatment of petroleum vapors. The process according to the invention provides valuable alkali 35 naphthenates and neutral high boiling distillates in yields which are not obtainable in prior art operation.

In another embodiment of the invention, lubricating oil distillates having satisfactory properties are obtained from the liquid alkaline material which is removed from 40 the alkali treating zone. In typical operation, such oil constitutes a major proportion of the liquid alkaline material, alkali metal naphthenates and excess alkali metal hydroxide being present in the liquid alkaline material in relatively small proportions. It is known in the art to 45 separate the alkali metal naphthenates and alkali metal hydroxide from the hydrocarbon constituents of the liquid alkaline material. According to this embodiment of the invention, heavy lubricating oil having satisfactory properties for various uses is obtained from the separated oil by distillation followed by contacting of the distillate obtained with hydrogen under conditions subsequently specified.

If desired, the residue obtained from the vacuum alkali tower, and the raffinate oil obtained by extraction 55 of alkali naphthenates from the liquid alkaline material can be distilled together to obtain a distillate comprising constituents distilled from both charge stocks, the distillate subsequently being subjected to contact with hydrogen under the conditions according to the invention.

The contacting with hydrogen according to the invention is performed at a temperature within the approximate range from 500° F. to 750° F., and preferably within the approximate range from 600° F. to 700° F. The pressure is within the approximate range from 100 p.s.i.g. to 2000 p.s.i.g., and preferably within the approximate range from 1000 p.s.i.g. to 1500 p.s.i.g. The contacting with hydrogen is performed in the presence of a hydrogenation catalyst. A preferred manner of contact-

ing involves passing the hydrocarbon charge stock downwardly through a stationary bed of granular solid hydrogenation catalyst, in the presence of hydrogen. Preferred space rates in such operation are those within the approximate range from 0.1 to 10 volumes of liquid charge per volume of catalyst bed per hour; more preferred space rates are those within the approximate range from 0.5 to 2.

Hydrogenation catalysts, as well known in the art, are generally suitable for use according to the invention. Examples of suitable catalysts are metals such as copper, zinc, magnesium, tin, vanadium, tungsten, chromium, molybdenum, manganese, cobalt, iron, nickel, platinum, etc., or oxides or sulfides of such metals, or mixtures of such metals, their oxides or sulfides. Any of the well known catalyst carriers can be employed according to the invention such as activated carbon, alumina, bauxite, charcoal, clay, kieselguhr, magnesia, pumice, silica, silica-alumina compositions, etc.

The invention will be further described with reference to the attached drawing, which is a schematic diagram of one embodiment of the process according to the invention.

As represented in the drawing, crude petroleum is introduced through line 10 into atmospheric topping tower 11, wherein it is subjected to distillation at atmospheric pressure to obtain distillates comprising gas oil and lighter petroleum fractions. In a treating section of tower 11, the vapors evolved from the crude are contacted with liquid alkaline material introduced through line 12. Liquid alkaline material containing alkali metal naphthenates and gas oil constituents condensed from the vapors, is withdrawn through line 13 and introduced into extraction zone 18. The residue from the distillation is introduced through line 14 into vacuum tower 15. Lubricating oil vapors containing naphthenic acids, which are evolved in tower 15, are passed upwardly through the alkali treating section, and contacted with alkali metal hydroxide introduced through line 16.

Liquid alkaline material, containing alkali metal naphthenates formed in the treating section and liquid lubricating oil condensed therein, is withdrawn through line 17. A portion of the withdrawn material is returned to the treating section through means not shown. Another portion is passed through means not shown into tower 11 to serve as the liquid alkaline material in that tower. Another portion of the liquid alkaline material is passed through line 17 into extraction zone 18, wherein it is contacted with aqueous isopropanol, introduced by means not shown, in order to extract alkali metal naphthenates from the liquid lubricating oil. The alkali metal naphthenates are withdrawn through line 19, and the raffinate oil is withdrawn through line 20 and introduced into vacuum distillation tower 21. If desired, a portion of the raffinate can be recycled through means not shown to the treating section of the vacuum alkali tower. Preferably, however, substantially all of the raffinate is introduced into tower 21. The residue from vacuum alkali tower 15 is withdrawn through line 22 and introduced into tower 21.

The residue and raffinate are distilled together in tower 21 to produce a heavy lubricating oil distillate which is introduced through line 23 into hydrogenation zone 24. Residue is withdrawn from tower 21 through line 25.

In zone 24, the distillate is contacted with hydrogen in the presence of a hydrogenation catalyst, under conditions specified previously. The hydrogenated heavy oil which is obtained in zone 24 is withdrawn through line 26, and can, if desired, be removed through line 27 as a product of the process. On the other hand, if further fractionation of the product is desired in order to obtain more narrow boiling products, the hydrogenated product can be introduced into a distillation zone wherein such narrow boiling products are obtained. This distillation zone can be a separate distillation zone not shown;

alternatively, the hydrogenated product can be introduced through line 28 into the rectification zone of tower 15, the narrow boiling products being obtained as side streams in the rectification zone. The distillate oils obtained from the alkali-treated vapors and from the hydrogenated oil are indicated generally by line 30, which represents a plurality of distillates of different boiling range.

If desired, a plurality of distillates of varying boiling range and viscosity can be obtained in distillation tower 21, and one or more of the distillates subjected to hydrogenation as indicated in zone 24. Alternatively, a single hydrogenation zone can be employed, any division of the heavy lubricating oil into different hydrogenated distillates being performed subsequent to the hydrogenation.

The Saybolt Universal viscosity at 210° F. of the hydrogenated product obtained according to the invention is within the approximate range from 100 to 200 seconds, and preferably within the approximate range from 120 to 150 seconds.

The following examples illustrate the invention:

Example I

A procedure generally similar to that illustrated in the drawing was carried out. Naphthenic crude petroleum having A.P.I. gravity of about 25 was distilled in the atmospheric alkali tower to obtain a residue (about 20 A.P.I.) constituting 55 to 60% of the crude. This residue was distilled in the vacuum alkali tower to obtain a residue constituting about 9.5% based on original crude. The feed inlet temperature for the vacuum tower was 650° F., and the flash zone pressure was 75 mm. of Hg absolute. The liquid temperature on the lowest tray of the treating section was about 630° F. The liquid temperature on the lowest tray above the treating section was about 600° F., and the condensate thereon, having Saybolt Universal viscosity at 210° F. of about 135 seconds, was passed downwardly into the treating section. The heaviest distillate removed from the tower had viscosity of 115 to 120 S.U.S. (Saybolt Universal seconds) at 210° F. and was removed at a temperature of about 585° F. By stripping off about 15 to 20% of light ends, the viscosity can be raised to about 135 S.U.S. The next heaviest distillate removed had viscosity of about 78 S.U.S. at 210° F. and was removed at a temperature of about 555° F. By stripping off about 5 to 15% of light ends, the viscosity can be raised to about 85 S.U.S. The residue from the vacuum alkali tower had A.P.I. gravity of about 12, and 210° F. viscosity of about 1000 S.U.S.

Typical yields of distillates obtained in the vacuum alkali tower are as follows: viscosity of 135 S.U.S./210° F., 2.6 volume percent; viscosity of 85 S.U.S./210° F., 9.1 volume percent; and lower viscosities, 23.0 volume percent.

The liquid alkaline material removed from the vacuum alkali tower contained about 83.5% oil, 15% alkali metal naphthenates, and 1.5% alkali metal hydroxide. The procedure for extracting naphthenates and alkali metal hydroxide from the material to obtain the oil as raffinate was as follows:

The alkaline material was contacted with 20 volumes of 30 to 32 weight percent aqueous isopropanol based on naphthenates in the alkaline material, and with one volume of 110 to 250° F. boiling range aviation alkylate based on oil in the alkaline material. After intimate contact, the mixture was stratified and the alcohol layer containing naphthenates and alkali metal hydroxide was separated from the alkylate layer containing oil. Alkylate was stripped from the oil to obtain a raffinate oil as residue. In cases where alkaline material from the atmospheric tower is included in the charge to alcohol extraction, the raffinate typically has Saybolt Universal viscosity at 210° F. of about 120 seconds. Where alkaline material from the vacuum tower only is charged, the 210° F. viscosity is typically about 280 seconds.

A series of vacuum distillations were made, to which were charged blends of vacuum alkali tower bottoms and raffinate oil from naphthenate extraction. These distillations were carried out in a vacuum flash tower from which a light and a heavy distillate were recovered. Nitrogen was added in the preheater coil to assist vaporization. The following table gives the data for the four distillations:

	Distillation Runs			
	No. 1	No. 2	No. 3	No. 4
Charge inlet temperature, ° F.	723	750	733	725
Flash zone pressure, mm. of Hg Abs.	41	54	40	38
Light Distillate:				
Vapor temperature, ° F.	575	480	530	575
Yield in vol. percent of charge	17.7	19.7	23.6	18.6
A.P.I. gravity of distillate	18.3	19.4	19.4	18.3
Viscosity of distillate, SUS/210° F.	66.7	50.6	49.2	68.2
Heavy Distillate:				
Liquid temperature, ° F.	635	668	637	638
Yield in vol. percent of charge	8.0	17.3	15.2	12.4
A.P.I. gravity of distillate	17.2	18.0	17.3	17.6
Viscosity of distillate, SUS/210° F.	157.6	150.3	162.1	143.2
Residue:				
Yield in vol. percent of charge	74.3	63.0	61.2	69.0
A.P.I. gravity of residue	13.1	13.1	12.5	13.6
Viscosity of residue, SFS/210° F. (Saybolt Furul Seconds)	144.6	159.5	219.4	136.2

Substantially higher yields of distillate can be obtained when a stripping medium, e.g. steam, is introduced directly into the vacuum tower. Thus, for example, about 45 percent of distillate having viscosity at 210° F. of about 107 S.U.S., can be obtained, using about 6 pounds of pre-heater steam and about 3 pounds of stripping steam per barrel of charge.

The charge to distillations Nos. 1 and 2 was a blend of 35 69 volume percent vacuum alkali tower bottoms and 31 volume percent raffinate oil from naphthenate extraction; naphthenates from the vacuum tower only were present in the extraction step. The charge to distillation No. 3 was a blend of 77 percent bottoms and 23 percent raffinate; naphthenates from both the atmospheric alkali tower and the vacuum alkali tower were present in the extraction step which produced the raffinate. The charge to distillation No. 4 was similar to the charge to distillation 40 No. 1 except that 9 percent of the raffinate oil was replaced, in the charge to distillation No. 4, by a heavy distillate oil from the vacuum alkali tower.

The light and heavy distillates from the four distillations were blended in the following approximate proportions:

Light distillates:	Volume percent
No. 1	4.05
No. 2	4.05
No. 3	11.5
No. 4	16.0
Heavy distillates:	
No. 3	34.9
No. 4	29.5
	100.00

The blend had A.P.I. gravity of 17.8 and Saybolt Universal viscosity at 210° F. of 107.5 seconds.

The blend was passed downwardly through a stationary bed of 8 to 14 mesh hydrogenation catalyst comprising 20% molybdenum disulfide on an activated alumina carrier, and was contacted with hydrogen during such passage under the conditions indicated in the following table, LHSV representing the liquid hourly space 70 velocity in volumes of charge per volume of catalyst bed per hour. No hydrogen was removed from the bed other than that dissolved in the effluent oil, and hydrogen was added in amount sufficient to replace that reacted with and dissolved in the oil.

	Charge Stock	Oil Hydrogenated at 1,300 p.s.i.g., 625° F.		
		LHSV 2.2	LHSV 1.0	LHSV 0.53
A.P.I. gravity	17.8	17.6	18.3	18.8
SUS at 210° F.	107.5	108.8	106.2	107.1
NPA Color	Too Dark	5	4 $\frac{1}{2}$	3 $\frac{1}{2}$
Aged NPA Color	Too Dark	Too Dark	7	5 $\frac{1}{2}$
Acid No.	0.87	0.07	0.03	0
R.I.	1.5228	1.5213	1.5202	1.5192

Distillation ° F.:		
	Initial	500
5%	677	703
10%	765	813
20%	842	862
50%	912	924
80%	965	970
90%	987	986
95%	1,002	1,000
98%	1,009	1,020

The properties given for the hydrogenated oils were obtained after stripping off small amounts (1.3 to 2%) of light ends formed in the hydrogenation. The aged NPA color was obtained after the oil stood at 220° F. for 16 hours in an atmosphere of air.

This example shows that distillate oils having good properties can be prepared, in a process involving distillation to produce a residue and vapors and refining of the vapors with liquid alkaline material, by distilling the residue and oil recovered from the liquid alkaline material, and contacting the distillate with hydrogen under hydrogenating conditions. The example further shows that increasing severity of hydrogenation, as provided here by decreasing space rate, results in improved 30 oils from the standpoint of color, color stability, acidity, etc.

In operation of the vacuum alkali tower, about 11 volume percent based on total crude of 107 S.U.S. at 210° F. distillate having NPA color of, for example, 4 can be obtained. Attempts to produce higher yields 40 result in decomposition and deposition difficulties in the alkali section and poorer color in the distillate. By way of contrast, in operation according to the invention, higher yields of 107 viscosity distillate having NPA color of 4 can be obtained. The following table provides a comparison of the obtainable yields in volume percent on total crude:

50	Operation	Yield of 107 SUS oil, NPA 4
Conventional		11
According to the invention		17

This example shows that operation according to the invention permits obtaining increased yields of heavy distillate oils having satisfactory color and other properties.

Generally, similar results can be obtained using either 60 vacuum alkali tower bottoms or raffinate oil from naphthenate extraction as as sole charge stock to the distillation. Also, the blending of distillates from a plurality of distillations to obtain the hydrogenation charge stock is of course not an essential feature of the invention. 65 Any of the higher viscosity distillates obtained in any of the distillations could be used as the sole hydrogenation charge stock.

Example II

Additional experiments were carried out according to the procedure of Example I, the distillation of vacuum alkali tower bottoms and raffinate oil being conducted however under somewhat different conditions, and the hydrogenation charge stock being a higher boiling fraction than that in Example I.

The distillation charge stock was a blend of 69 volume percent vacuum soda tower bottoms and 31 volume percent raffinate oil from naphthenate extraction; naphthenates from both the atmospheric soda tower and the vacuum soda tower were present in the extraction step. The following table gives the data for the distillation:

Charge inlet temperature, °F	725
Flash zone pressure, mm. of Hg absolute	57
Heavy Distillate:	
Liquid temperature °F	695
Yield in vol. percent of charge	31.1
A.P.I. gravity	16.9
Viscosity, SUS/210° F	157.0
Residue:	
Yield in vol. percent of charge	55.9
A.P.I. gravity	13.2
Viscosity, SFS/210° F	161.0

The heavy distillate was employed as the charge to the hydrogen contacting operation, which was conducted generally similarly to that in Example I, the conditions being 675° F., 1300 p.s.i.g., and LHSV 1.3. The data are given in the following table:

	Charge	Product
A.P.I. gravity	17.3	18.2
SUS at 210° F.	156.7	119.7
NPA Color	Too Dark	4
Aged NPA Color	Too Dark	54
Acid No.	0.49	0
R.I.	1.5243	1.5203
Distillation, ° F.:		
Initial	794	563
5%	819	809
10%	833	828
50%	931	926
90%	1,019	1,022
93%		1,033
94%		1,033

By stripping about 3% of light ends from the product, the viscosity was raised from 119.7 to 136.5.

This example shows that heavy distillates having good properties can be obtained in a manner generally similar to that involved in Example I, but producing a product having higher viscosity than that obtained in Example I. In order to obtain, in operation of the vacuum alkali tower, a 136.5 viscosity distillate in yields corresponding to that obtained in this example, the temperature in the alkali treating section would have to be raised to a level causing severe decomposition and carbon deposition difficulties.

The following table shows the yields of good quality heavy oil obtainable according to the invention, as compared with conventional operation; yields are given in volume percent, based on total crude:

Operation	Yield of 136.5 SUS oil, NPA 4
Conventional	216
According to the invention	6

This example shows the high yields of good quality oil having Saybolt Universal viscosity at 210° F. of 136.5 seconds, obtainable according to the invention.

Example III

Vacuum alkali tower bottoms produced as described

in Example I are vacuum distilled in the absence of raffinate oil from naphthenate extraction. The charge stock is a blend of 75 percent of the bottoms and 25 percent of gas oil obtained as distillate in the vacuum alkali tower. The charge stock is preheated to 750° F. and introduced into a flash zone at 64 mm. of Hg absolute. A heavy distillate having 210° F. viscosity of 179 S.U.S. is obtained, the yield being about 20 volume percent of the distillation charge. This distillate is charged to a hydrogenation operation conducted similarly to that in Example I, the conditions being 700° F., 1500 p.s.i.g., and LHSV 3. The product obtained, after stripping of light ends, has approximately the same viscosity as the heavy distillate prior to hydrogenation, has good color and color stability, and is neutral. In conventional operation it is impossible to obtain such a high viscosity distillate without severe operating difficulties because of the high temperatures involved.

This example shows that operation according to the invention permits obtaining higher viscosity distillates than are obtainable in conventional vapor phase alkali treating processes.

The invention claimed is:

1. Process for refining petroleum which comprises: distilling petroleum containing naphthenic acids and lubricating oil constituents to obtain a vaporized portion containing naphthenic acids and to obtain a residue; contacting said vaporized portion under vapor phase treating conditions with liquid alkaline material in a treating zone, thereby to form alkali metal naphthenates and to condense relatively high boiling hydrocarbon constituents of said portion; removing treated vapors from the treating zone; removing said high boiling hydrocarbon constituents from said liquid alkaline material; distilling in the absence of liquid alkaline material a charge stock selected from the group consisting of (1) said residue, (2) said high boiling hydrocarbon constituents, and (3) mixtures of said residue and said high boiling hydrocarbon constituents, thereby to obtain a distillate having Saybolt Universal viscosity at 210° F. within the approximate range from 100 to 200 seconds; contacting the last-named distillate with hydrogen at 500 to 750° F. and 100 to 2000 p.s.i.g. in the presence of a hydrogenation catalyst to obtain a hydrogenated distillate; and blending said hydrogenated distillate and said treated vapors to obtain distillates containing constituents of both.
2. Process according to claim 1 wherein said blending is performed by admixing said hydrogenated distillate and said treated vapors and distilling the resulting mixture to obtain said distillates.
3. Process according to claim 1 wherein said charge stock is said residue.
4. Process according to claim 1 wherein said charge stock is said high boiling hydrocarbon constituents.
5. Process according to claim 1 wherein said charge stock is a mixture of said residue and said high boiling hydrocarbon constituents.
